UNITED STATES PATENT OFFICE.

ALVIN W. KNAPP, OF BRANDON, NEW YORK.

OAR-LOCK.

SPECIFICATION forming part of Letters Patent No. 724,298, dated March 31, 1903.

Application filed July 25, 1902. Serial No. 116,966. (No model.)

To all whom it may concern:

Be it known that I, ALVIN W. KNAPP, a citizen of the United States, residing at Brandon, in the county of Franklin and State of New York, have invented certain new and useful Improvements in Oar-Locks, of which the following is a specification.

This invention aims to provide a support of novel formation for an oar-lock to admit 10 of adapting said oar-lock to the reach of the person rowing, so as to enable the force expended to be applied to the best possible advantage without producing the fatigue and inconvenience resulting from a cramped position 15 in cases of non-adjustment of the oar-lock.

In the general construction of oar-locks the same when positioned occupy a definite distance from the seat. Consequently tall and 20 short persons must adapt themselves to the distance, at a great disadvantage to one or the other. This invention provides a mounting which will admit of shifting the oar-lock toward and from the seat, according to the reach 25 of the rower, thereby obviating the ills attendant upon the construction in which the oar-lock maintains a uniform distance or position with reference to the seat.

For a full description of the invention and 30 the merits thereof, and also to acquire a knowledge of the details of construction of the means for effecting the result, reference is to be had to the following description and drawings hereto attached.

35 While the essential and characteristic features of the invention are susceptible of modification, still the preferred embodiment of the invention is illustrated in the accompanying drawings, in which—

40 Figure 1 is a perspective view of the side portion of a boat, showing an oar-lock mounted in accordance with this invention. Fig. 2 is a perspective view of the mounting or plate detached from the boat. Fig. 3 is a 45 perspective view of a modification. Fig. 4 is a horizontal or plan section thereof.

Corresponding and like parts are referred to in the following description and indicated in all the views of the drawings by the same 50 reference characters.

The mounting for the oar-lock consists of

a plate 1, provided with a series of sockets 2 at intervals in its length, said plate being adapted to be bolted or otherwise secured to the gunwale of the boat in any substantial 55 manner. The sockets 2 may be of any formation and provided in any number, according to the required adjustments of the oar-lock to vary its position from the seat 3 of the boat. While it is preferred to have the 60 sockets 2 integral with the plate 1, it is contemplated within the purview of the invention to construct the sockets separate from the plate and attach them thereto, about as shown in Figs. 3 and 4. 65

The oar-lock 4 may be of any pattern or make, and its stem is removably fitted in any one of the sockets 2, so as to admit of moving the oar-lock toward or away from the seat 3, according to the reach or convenience of 70 the rower. A short person or rower having a short reach can manipulate the oar to the best possible advantage by having the oar-lock fitted into the socket nearest the seat, and a tall person or one having a long reach 75 can row to advantage by having the oar-lock fitted in the socket farthest from the seat. The mounting herein disclosed provides for adjustment of the oar-lock to meet varying requirements, so that the position of the oar-lock may be such as to adapt it to the reach 80 of the rower.

In the construction shown in Figs. 3 and 4 the plate 1 is provided with pairs of ribs 5, which are undercut and converge slightly 85 toward their lower ends, whereby the space between the vertical edges of corresponding ribs contracts toward its lower end, so as to prevent downward displacement of the socket 2^a. The socket 2^a is widened at its rear side 90 to form lateral extensions 6, which are downwardly converged conformable to the space formed between a pair of ribs 5. The lateral extensions 6 are beveled so as to interlock with the undercut edges of the ribs 5 and 95 form interlocking connection therewith to hold the socket in place. The slight taper of the space between a pair of ribs 5 is such as to cause the lateral extensions or wings 6 to bind frictionally against said ribs to retain 100 the socket in place. However, positive securing means may be employed for holding the

socket to the plate against vertical displacement, and, as shown in Fig. 3, the cotter-pin 7, applied to the stem of the oar-lock 4, may engage under the plate 1. By having the 5 socket 2^a detachably connected with the plate the mounting may be constructed of less metal, and only one socket projects laterally from the plate instead of a plurality, as is the case where a series of sockets and the 10 plate are integrally formed.

Having thus described the invention, what is claimed as new is—

1. A mounting for an oar-lock to admit of adjustment of the oar-lock to a greater or less 15 distance from the seat of the rower, said mounting consisting of a plate, and a series of separate and independent securing means provided at intervals for attachment of the oar-lock to the plate in any selected position, 20 substantially as set forth.

2. A mounting for an oar-lock, the same consisting of a plate provided with ribs at intervals in its length, and a socket shiftable along the plate and adapted to make inter-

locking connection with any pair of the said 25 ribs of said plate, substantially as set forth.

3. A mounting for an oar-lock consisting of a plate provided with pairs of ribs at intervals in its length, and a socket having a side widened to provide lateral extensions to make 30 interlocking connection with the ribs of any one of the said pairs of ribs, substantially as described.

4. A mounting for an oar-lock consisting of a plate provided with pairs of ribs having 35 the opposing edges of each pair of ribs undercut and downwardly converged, and a socket having a side widened and provided with lateral extensions which are beveled and downwardly converged to make interlocking connection with any one of the said pairs of ribs, 40 substantially as set forth.

In testimony whereof I affix my signature in presence of two witnesses.

ALVIN W. KNAPP. [L. S.]
